UNITED STATES PATENT OFFICE.

LOUIS L. ANSART, OF NEW YORK, N. Y., ASSIGNOR TO UNDERWOOD COMPUTING MACHINE COMPANY, OF NEW YORK, N. Y., A CORPORATION OF NEW YORK.

COMPUTING MACHINE.

Application filed January 25, 1921. Serial No. 439,723.

To all whom it may concern:

Be it known that I, LOUIS L. ANSART, a citizen of the United States, residing in borough of the Bronx, in the county of the Bronx, city and State of New York, have invented certain new and useful Improvements in Computing Machines, of which the following is a specification.

This invention relates to improvements in computing machines capable of effecting algebraic computations, and of indicating the correct results whether positive or negative, and is in the nature of an improvement on the application of Louis E. Giles, Serial No. 392,964, filed June 30, 1920 (now Patent No. 1,414,355, dated May 2, 1922).

In the machine disclosed in said application the opening in the casing must be wide enough to expose three rows of figures, and when the shutter is in its normal position, there is exposed, in addition to the row of positive digits from which the correct reading of positive results may be obtained, a row of negative digits at one side thereof. Also, when the shutter is positioned to give the correct reading of the negative result, such result must be read from two rows of negative digits on opposite sides on the row of positive digits and certain digits in the row of positive digits will always be exposed. Obviously, the showing of unnecessary digits both when reading positive results or negative results and the necessity for reading negative results from two rows, give rise to an undesirable condition, in that there is a tendency to confuse the operator in reading such results. It should be understood that such machines may be modified to enable reading of negative results from one row, and to necessitate the reading of positive results from two rows.

An object of the present invention is to provide means whereby upon changing from a positive to a negative result, or vice versa, the result may be read from a single row of digits without shifting the units wheel to run in the fugitive unit.

Another object of the invention is to obtain a totalizer or register in which both positive and negative results may be read from the same row of digits.

Another object of the invention is to provide a totalizer and shutter such that the latter may be utilized to point out in a row of positive and negative digits in the nu-

meral wheels the positive digits from which the corresponding positive result is to be read or the negative digits from which a negative result is to be read.

A further object of the invention consists in so arranging the positive and negative digits on the numeral-wheels, and providing a shutter of such shape that, when the shutter is positioned for reading a positive result, all of the negative digits will be obscured, and that, when the shutter is properly positioned for reading a negative result, all of the digits except those from which the correct negative result is read will be obscured.

In carrying out the invention, the numerals from which positive results may be read, called positive digits, and the digits from which negative results may be read, called negative digits, may be arranged in three different sets, peripherally of each of the numeral-wheels, one of said sets being of one kind of digits and the other two of the other kind of digits. These digits may also be arranged in rows of three across the periphery, the two digits of the same kind in each row being complements to the base nine and ten, respectively, of the digit of the other kind in said row. Provision may also be made of means for directing attention to a row of digits extending across all of the numeral-wheels from which both positive and negative results may be read, without shifting the units wheel in order to run in the fugitive unit.

In case the single digit of one kind in each row of three extending across the periphery of a numeral or number-wheel is a positive digit, positive results or the complements of negative results may always be read from the positive digits in the row above referred to, and negative results may be read from certain negative digits in said row. In order to facilitate the reading of such positive and negative results, provision may be made of a shutter, which, in its normal position, leaves exposed all of the positive digits and covers or obscures all of the negative digits in said row, from which readings are to be taken, and which, in case of a negative result, when properly positioned in accordance with the position of the last significant digit in the complement of said negative result, will expose only the negative digits, from which the correct nega-

tive result may be read, and will cover or obscure all of the positive digits and all of the erroneous negative digits. Preferably, the positive and negative digits are of characteristic appearance, so that they may be easily distinguished from each other, but this difference in appearance is not essential in view of the fact that the shutter will always conceal all of the erroneous digits.

10 Preferably, for a reason to be brought out later, the arrangement of digits on each wheel is such that, in each transverse row, the positive digit will appear in the middle, the negative digit, complementary thereof to the base "10" appearing to the left thereof, and the negative digit, complementary to the base "9", appearing to the right thereof. The arrangement of the negative digits, with reference to the positive digits, may be reversed, relative to the arrangement just described, and still other arrangements of the digits in each row of three may be made. Obviously, with a proper organization of the machine, one set of negative digits and two of positive digits may be used on each wheel.

Positive and negative results may be read directly from the number-wheels without the use of a shutter, the correct positive result being always readable directly from the positive digits in case of the preferred arrangement of the digits on the numeral-wheels, and the correct negative result may be read by reading the digits complementary to the base "9" of those digits of the complement of the negative result, down to the last significant figure of the latter, and then the digits complementary to the base "10" of the remaining digits of said complement. In order to facilitate the reading of such results, however, provision may be made of a shutter or reading gage having a set of digit-exposing openings, suitably spaced so that, when the shutter is properly positioned, only the positive digits may be exposed therethrough, and having a second set of digit-exposing openings similarly spaced, the openings of the two sets being so positioned, with reference to each other, that, when the openings of the first set are positioned to expose the complements to the base "9" of the positive digits in the row from which readings are to be taken, the openings of the second set, which are to the right of those of the first set, will expose negative digits complementary to the base "10" of the corresponding positive digits in the reading row. It should be understood that, with the digits arranged in the preferred form on the numeral-wheels, the openings at the adjacent ends of the two sets in the shutter will come together, and the length of the shutter will be less than that required in case the arrangement is the reverse of the preferred form. It should also

be understood that use may be made of a reading gage adapted merely to point out, when properly positioned, the digits to be read.

Other features and advantages will hereinafter appear. 70

In the accompanying drawings,

Figure 1 is a fragmentary plan view of an Underwood bookkeeping machine, showing the present invention applied thereto. 75

Figure 2 is a view of a portion of Figure 1 on a large scale, showing a positive number registered upon the computing wheels, and the reading gage, or shutter, in its normal position to enable reading of the positive result. 80

Figure 3 is a view similar to Figure 2, but showing a negative number registered upon the computing wheels, the last significant figure of the complement of the negative number being on the units wheel and the shutter positioned accordingly. 85

Figure 4 is a view similar to Figure 3, showing a negative number registered upon the computing wheels, and the reading gage for the shutter positioned properly, the position of the shutter being determined by the last significant figure of the complement of the negative result, which in this figure is on a computing wheel other than the units computing wheel. 90

Figure 5 is a fragmentary perspective view of the shutter, parts of which are broken away. 95

Figure 6 is a developed view of the periphery of one of the numeral-wheels used in connection with the present invention. 100

Figure 7 is a fragmentary sectional side view of that part of the device shown in Figure 1 bringing out the relationship of the computing wheels and the shutter. 105

Figure 8 is a perspective view of one of the computing wheels, showing a notch extending across the periphery thereof.

Figure 9 is a developed view of the periphery of a computing or numeral-wheel of a modified form, the digits on each side of a central digit being reversed with reference to the position of the same digits, as shown in Figure 6. 110

The Underwood bookkeeping machine, to which this invention is applied, includes a typewriter-frame 10, a computer casing 11, typewriter-keys including numeral-keys 12, and numeral-wheels 13, the latter being revolvably mounted in the casing 11 and actuatable for addition or subtraction by computing mechanism including pinions 14 having one-way connections with said numeral-wheels, one form of such mechanism being disclosed in the patent to Hans Hanson, No. 1,278,812, granted September 10, 1918. 120

The positive and negative digits are preferably shown on the number-wheels, as usual, in black and red, respectively, and are in- 125

dicated on the drawings by means of solid and open figures, respectively. In the preferred arrangement, shown in Figure 6, the positive digits are arranged in one direction around the periphery, and the negative digits are arranged in the opposite direction, so that on the left side of each positive digit appears a negative digit complementary thereof to the base "10", and on the right a negative digit complementary to the base "9". The positive and negative digits for each numeral-wheel may be inscribed on a celluloid strip of substantially the usual form. Obviously, the digits for each numeral-wheel may be on a single strip, or each set of digits may be on a separate strip. In case the positive and negative digits are on separate strips, it will be a comparatively simple matter to change from the arrangement shown in Figure 6 to that shown in Figure 9.

Machines of this character are used only for computations in which the results lie sufficiently within the range of the register that no digit of the result will be registered on the wheel of highest denomination, this wheel serving only to indicate whether the result is positive or negative, being moved backward and forward only one step, to show a positive "0" through the sight-opening 16, thereby indicating a positive result, or to show a positive "9" through said sight-opening, thereby indicating a negative result. In case the positive "0" lies at the sight-opening, the positive result may be read from the positive digits on the numeral-wheels, and, in case a positive "9" lies at the sight-opening, the number read from the positive digits will be the complement of the correct negative result, which may be read by means of the negative digits complementary, to the base "9", to the positive digits until the last significant digit of the positive digits is reached, and then by reading the negative digits which are complementary, to the base "10", to the remaining positive digits. It will be evident that the left-hand negative digit on the numeral-wheel of highest denomination and the right hand negative digit on the numeral-wheel of lowest denomination will never be used, thereby enabling the sight-opening to be shortened, so that the portions of the wheels of highest and lowest denominations, on which are the digits just referred to, will be hidden from view by the casing.

In reading the results as just described, other digits than those necessary in reading the result will be seen in the single row of digits displayed at said sight-opening. According to the present invention, provision is made of a shutter or reading-gage 17, by which attention may be called to the proper positive digits, giving a correct positive result, or to the proper negative digits

from which a correct negative result may be read. As herein disclosed, the shutter or gage is provided at its left with a series of openings 18, so spaced that, when the shutter is placed with one of the openings 70 over a digit on one of said numeral-wheels, the other openings will be positioned over corresponding digits on the other numeral-wheels. For example, as shown in Figure 2, when the shutter is in its normal position, the positive digits on the various numeral-wheels will be displayed through the sight-openings 18, and all of the negative digits will be covered or obscured. The shutter is also provided with a second series of openings 19, having the same spacing as those of the first set, and so positioned relatively to the first series that the adjacent end openings of the two series will come together and form one opening 20 of double width.

In case the numeral-wheels are turned to show at the sight-opening, as in Figure 2, a positive "0" on the numeral-wheel of highest denomination, it will be understood that the result of the computation is positive and the result "247640" will be read from the positive digits displayed through the openings 18 in the shutter 17 when it is in its normal position, with a finger-piece 21 thereon in a notch or recess 22 in the casing 11 at the right-hand end of the sight-opening 16. It will be seen that in case the shutter is moved to its extreme left-hand position with the finger-piece 21 resting in a second notch 22, positive results may be read through the set of openings 19.

When the numeral-wheels are brought to the position shown in Figure 3, in any manner, as, for example, by subtracting "309614" 105 from the positive number "247640," shown in Figure 2, the appearance of the positive "9" of the numeral-wheel of highest denomination will indicate that the result is negative. In order to read such negative result, the shutter 17 is moved to the left to bring the solid portion at the right of the sight-opening 20 over the last significant digit, which, in this case, is the digit "6" 110 on the numeral-wheel of lowest denomination. The correct negative result "61974" 115 may then be read through said shutter. In connection with setting the shutter to read a negative result, the typist has only to bear in mind one commonly accepted definition 120 of a significant digit, namely, that it is one of the numerals from "1" to "9", inclusive.

If the numeral-wheels are then brought to the position shown in Figure 4, as, for example, by subtracting "636026" from the result shown in Figure 3, the shutter is moved farther to the left than for reading in Figure 3, the last significant positive digit in this case being on the fourth wheel from the right of the register. With the shutter so positioned, the correct negative result 130

"698000" may be read through the shutter. It should be understood that after taking a reading, the shutter 17, if displaced from its normal position in taking said reading, should be restored thereto as soon as the act of reading is completed. The shutter may be slidably mounted in grooves in guide-blocks 23, fastened to the casing 11 by means of screws 24; and the restoration of the shutter to its normal position, after taking a negative reading, may be effected by means of a spring 25, attached at one end to a lug 26 fixed on the shutter, and at the other end to a fixed part of the machine. In order that the shutter, in its movement to the left from its normal position, may be stopped at the proper position to give the correct negative reading, provision may be made of a lug or projection 27, adapted to enter grooves 28 in the right-hand numeral-wheels when such wheels are positioned to show a positive "0" at the sight-opening. As indicated in Figure 3, the lug 27 prevents the shutter from being moved farther to the left in Figure 3 than is necessary to cover the positive "6" appearing on the numeral-wheel of lowest denomination; said lug serving to engage the fourth numeral-wheel when the numeral-wheels are positioned, as shown in Figure 4, to cause the portion of the shutter immediately to the right of the double opening to cover the positive digit on said fourth wheel from the right. The ends of the grooves 28 in the various numeral-wheels may be beveled so as to facilitate the entrance of the lug 27 therein, when the numeral-wheels are slightly displaced from their proper positions.

It is evident that in case of a negative result, such result is read from the negative digits complementary, to the base nine, to the positive digits appearing at the sight-opening, until the last significant positive digit is reached, and then from the negative digits which are complementary, to the base ten, to the remaining positive digits. When the arrangement of negative digits with reference to the positive digits is that shown in Figure 6, it will be evident that the digits of the higher denominations in the negative result will be read from the right-hand negative digits on certain of the numeral-wheels, and the remainder of the result will be read from the left-hand negative digits, thus enabling the use of a shutter in which the adjacent openings 18 and 19 of the two sets come together and form an opening of double width. In case the arrangement of digits is that shown in Figure 9, it will be evident that the digits of higher denominations in a negative result will be read from the left-hand digits on the numeral-wheels, and that another digit, or digits, of lower denomination will be read from the right-

hand negative digits, which would necessitate the spacing apart of the adjacent openings 18 and 19 in the shutter, so that the right-hand opening 18 would be positioned opposite a negative digit at the left of one numeral-wheel, and the left-hand opening of the set of openings 19 would be positioned opposite the right-hand negative digit on the numeral-wheel of next lower denomination.

It will be evident, therefore, that a shutter for use with numeral-wheels having the arrangement shown in Figure 9 would be longer than one for use with numeral-wheels having the arrangement of digits as that shown in Figure 6; and, furthermore, that the sight-opening would have to be of greater length to expose the right-hand negative digit on the numeral-wheel of lowest denomination.

It would be possible to use the right-hand set of openings 19 to point out the correct figures of the positive result and to read the negative result by moving the shutter to the right to proper position for such reading. It is found, however, that it is much easier to properly locate the shutter by moving it to the left, as disclosed herein, to the position in which the solid portion of the shutter to the right of the double opening covers the last significant positive digit.

Another advantage of the present arrangement resides in the fact that the proper position of the shutter may be determined by means of the lug 27, further movement of the shutter to the left being prevented when said lug engages the right-hand side of the wheel of lowest denomination having a positive significant digit thereon.

Variations may be resorted to within the scope of the invention, and portions of the improvements may be used without others.

Having thus described my invention, I claim:

1. In an algebraic computing machine, in combination, dials having figures to represent positive values, and other figures to represent negative values, each dial having one set of one kind of figures and two sets of the other kind, and means whereby attention may be directed to a row of figures of the first set to give a correct reading of a result corresponding to the kind of figures in said set, and whereby attention may be directed to a row of figures of the other two sets from which results of the corresponding kind may be read.

2. In an algebraic computing machine, in combination, dials, including one for each of a plurality of denominations, as units, tens, etc., said dials having both positive and negative figures, each dial having one set of one kind of figures and two sets of the other kind, and means for directing attention to a row of figures of the first kind

115

120

125

130

from which results of that kind may be read, and for directing attention to a row of figures of the other two sets from which results of the corresponding kind may be 5 read.

3. In a computing machine, the combination with a set of dials, each having a set of positive digits arranged around its periphery, a negative digit at one side of each 10 positive digit and complementary thereto to the base nine, and a negative digit at the opposite side of the positive digit, complementary thereto to the base ten, of a cover 15 for said dials having a sight-opening to expose a single line of positive and negative digits, to enable positive results to be read from the positive digits and negative results 20 to be read on some of the dials from the negative digits complementary, to the base nine, to the positive digits at the sight-opening, and on the remaining dials from the negative digits complementary, to the base ten, to the associated positive digits.

4. In an algebraic computing machine, in 25 combination, a series of dials, each having a series of positive digits and two series of negative digits, said digits arranged one under another upon said dials, so that, on 30 one side of each positive digit, there is a negative digit complementary to the base nine, and on the other a negative digit complementary to the base ten, and means to indicate a row of digits from which results 35 may be read, a positive result or the complement of a negative result being read from the positive digits, and, in case of the latter, the correct negative result being read from the negative digits complementary to the base nine until the last significant figure of 40 the complement of the negative result is reached, and then from the negative digits complementary to the base ten.

5. In an algebraic computing machine, in 45 combination, a series of dials having positive and negative digits thereon, each of said dials having thereon a set of digits of one kind and two sets of digits of the other kind, all of the digits arranged one following another on said dials, so that, on one side 50 of each digit of the first set, there is a digit complementary to the base nine, and on the other a digit complementary to the base ten, and means to indicate a row of digits from which the results of computations may be 55 read, a result of the first kind or the complement of a result of the second kind being read from the digits of the first set, and, in the case of the latter, the correct result of the second kind being read from the digits 60 of the second kind complementary to the base nine until the last significant figure of the complement of the result of the second kind is reached, and then from the digits of the second kind complementary to the base 65 ten.

6. In an algebraic computing machine, the combination with dials, each having thereon positive and negative digits, of a shiftable shutter, so shaped that, when properly positioned, there will be exposed therethrough only positive digits, giving a correct reading of a positive result or the complement of a negative result, and, in the latter case, when moved to another position, while the dials remain in the same positions, there will be exposed therethrough only the negative digits giving the proper negative result. 70

7. In an algebraic computing machine, the combination with dials, each having thereon positive and negative digits, of a shiftable shutter, having in alignment, transversely of the dials, digit-exposing openings, so arranged that, when the shutter is properly positioned, there will be exposed therethrough positive digits, giving a correct reading of a positive result or the complement of a negative result, and, in the latter case, when moved to another position, there will be exposed therethrough only the negative digits giving the proper negative result. 80

8. In an algebraic computing machine, the combination with dials, each having thereon positive and negative digits, of a manually-operable shutter, so shaped that, when properly positioned, attention will be directed to positive digits in a certain row, giving a correct reading of a positive result or the complement of a negative result, and, in the latter case, when moved to another position, attention will be directed to negative digits in said row, giving the proper negative result. 95

9. In an algebraic computing machine, the combination with dials, each having thereon positive and negative digits, of means directing attention to a single row of positive and negative digits on said dials, and a shutter shiftable transversely of the dials, and so shaped that, when properly positioned, attention will be directed to positive digits in said row, giving a correct reading of a positive result or the complement of a negative result, and, in the latter case, when moved to another position, attention will be directed to negative digits in said row, giving the proper negative result. 105

10. In combination, a set of dials, each having a set of positive digits arranged in one direction and two sets of negative digits arranged in the opposite direction, so that the digits will lie in rows of three across the dial, the two negative digits in any row being on opposite sides of the positive digit and complementary thereto to the base nine and to the base ten, respectively, a shiftable shutter having two sets of openings in alignment, the openings of each set being spaced 110 115 120 125 130

so that correspondingly positioned digits on the different dials may be exposed therethrough simultaneously, said sets of openings being so positioned that the adjacent 5 openings of the two sets merge, forming a central opening of double width, and a handle for said shutter attached thereto at a point opposite the middle of the double-width opening.

10 11. In combination, a set of dials, each having a set of positive digits arranged in one direction, and two sets of negative digits arranged in the opposite direction so that the digits will lie in rows of three across 15 the dial, the two negative digits in any row being on opposite sides of the positive digit and complementary thereto to the base nine and to the base ten, respectively, a shutter having two sets of openings in alignment, 20 the openings of each set being spaced so that correspondingly positioned digits on the different dials may be exposed therethrough simultaneously, said sets of openings being so positioned that the adjacent openings of 25 the two sets merge, forming a central opening of double width, a handle for said shutter attached thereto at a point opposite the middle of the double-width opening, and a casing for said dials having a sight-opening 30 of sufficient length to expose all digits in the reading row, except the left-hand negative digit on the extreme left-hand dial, and the right-hand negative digit on the extreme right-hand dial, said casing having a notch 35 at each end of said sight-opening to receive said handle.

12. In combination, a set of dials, each having a set of positive digits arranged in one direction, and two sets of negative digits 40 arranged in the opposite direction so that the digits will lie in rows of three across the dial, the two negative digits in any row being on opposite sides of the positive digit and complementary thereto to the 45 base nine and to the base ten, respectively, a shiftable shutter having two sets of openings in alignment, the openings of each set being spaced so that correspondingly positioned digits on the different dials may be 50 exposed therethrough simultaneously, said sets of openings being so positioned that the adjacent openings of the two sets merge, forming a central opening of double width. a handle for said shutter attached thereto 55 at a point opposite the middle of the double-width opening, and a lug on said shutter adapted to enter grooves in said dials when the latter are positioned with the positive zeros thereon in the reading line, said lug 60 being at a distance from said handle substantially the same as the width of a dial.

13. In an algebraic computing machine, the combination with dials, each having thereon a set of positive digits and two sets 65 of negative digits, of a shutter shiftable

transversely of the dials along a certain row of digits thereon, and so shaped that, when properly positioned, the positive digits in said row will be exposed to give the correct reading of a positive result and all 70 the negative digits in said row, covered or obscured, and, in case of a negative result, when properly positioned, negative digits partly from one set thereof and partly from 75 the other will be exposed to give the correct reading of the negative result, and concomitantly all of the positive digits in said row and all the erroneous negative digits in said row will be covered or obscured.

14. A reading-gage for use in an adding and subtracting machine, having dials with positive and negative digits thereon, each dial having a set of digits of one kind and two sets of digits of the other kind, said digits arranged one under another, and, each digit of the first set having in line therewith, across the dial, a digit of one of the other sets which is a complement thereof to the base nine and a digit of the remaining set which is a complement thereof to the base ten, said gage adapted to overlie one row of digits on said dials, and, when properly positioned, to obscure in said row 90 all of the digits of the two sets of the same kind, so that the correct reading of a result of the first kind may be read from digits of the first set, positioned in said row, and, in case of a result of the other kind, to obscure in said row all digits of the first set and all erroneous digits of the other two sets.

15. A reading-gage for use in an adding and subtracting machine, having dials with digits arranged one under another thereon, each dial bearing positive and negative digits thereon and having a series of one kind and also a series of the other kind on each side of the first series, the digit on one side of each digit of the middle series being a complement thereof to the base nine, and the digit on the other side being a complement thereof to the base ten, said gage having a row of single-digit-exposing openings, spaced so as to expose only digits of corresponding series on the different dials, and a second row of similar and similarly-spaced openings in alignment with the first, at one end thereof, the two series of openings being so positioned relatively to each other that, when both are partly in use, digits which are complementary to the base nine of the middle digits will be exposed on certain dials through the left-hand series of openings, and the digits which are complementary to the base ten relative to the middle digits may be seen through the openings of the right-hand row, all the erroneous digits being obscured.

16. A denominational element for an 130

algebraic computing machine having positive and negative digits thereon, a set of digits of one kind being arranged in order around the periphery thereof, and two sets 5 of the other kind of digits arranged in the opposite direction, so that the digits will be arranged in transverse rows of three, and the two digits of the same kind in each transverse row will be complementary, to 10 the base nine and to the base ten, respectively, to the digit of the first set.

17. A numeral-wheel for use in an algebraic computing machine, having a set of positive digits arranged in order thereon 15 around in one direction, and two sets of negative digits arranged in order thereon in the opposite direction, so that in line with each positive digit there will be two negative digits, one complementary there- 20 to to the base nine and the other to the base ten.

18. In an algebraic computing machine, the combination with dials, each having thereon positive and negative digits, of a 25 shiftable shutter so shaped that when in its normal right-hand position attention will be called to positive digits in a certain row, giving a correct reading of a positive result or the complement of a negative result, and 30 in the latter case, when moved to another position, attention will be called to negative digits in said row, giving the proper negative result, and means to stop the left- 35 ward movement of the shutter when it has reached the proper position for reading the negative result.

19. In an algebraic computing machine, the combination with numeral-wheels, each having thereon positive and negative digits, 40 of a manually-operable shutter so shaped that when in its normal right-hand position attention will be called to positive digits in a certain row, giving a correct reading of a positive result or the complement of a 45 negative result, and in the latter case, when moved to another position, attention will be called to negative digits in said row, giving the proper negative result, means to stop the leftward movement of the shutter 50 when it has reached the proper position for reading the negative result, and means normally urging said shutter to its right-hand position.

20. In combination, a set of dials, each 55 having a set of positive digits arranged in one direction and two sets of negative digits arranged in the opposite direction, so that the digits will lie in rows of three across the dial, the two negative digits in any row 60 being on opposite sides of the positive digit and complementary thereto to the base nine

and to the base ten, respectively, and a shift- 65 able shutter having two sets of openings in alignment, the openings of each set being spaced so that correspondingly positioned digits on the different dials may be exposed therethrough simultaneously, said sets of openings being so positioned that the adjacent 70 openings of the two sets merge, forming a central opening of double width.

21. In combination, a set of dials, each having a set of positive digits arranged in one direction and two sets of negative digits arranged in the opposite direction so that the digits will lie in rows of three across the 75 dial, the two negative digits in any row being on opposite sides of the positive digit and complementary thereto to the base nine and to the base ten, respectively, a shutter having two sets of openings in alignment, 80 the openings of each set being spaced so that correspondingly positioned digits on the different dials may be exposed therethrough simultaneously, said sets of openings being so positioned that the adjacent 85 openings of the two sets merge, forming a central opening of double width, and a casing for said dials having a sight-opening of sufficient length to expose all digits in the reading row, except the left-hand negative 90 digit on the extreme left-hand dial, and the right-hand negative digit on the extreme right-hand dial, said casing having a notch at each end of said sight-opening and said shutter having locating means to engage 95 said notches.

22. In combination, a set of dials, each having a set of positive digits arranged in one direction and two sets of negative digits arranged in the opposite direction so that 100 the digits will lie in rows of three across the dial, the two negative digits in any row being on opposite sides of the positive digit and complementary thereto to the base nine and to the base ten, respectively, a shift- 105 able shutter having two sets of openings in alignment, the openings of each set being spaced so that correspondingly positioned digits on the different dials may be exposed therethrough simultaneously, said sets of 110 openings being so positioned that the adjacent openings of the two sets merge, forming a central opening of double width, and a lug on said shutter adapted to enter grooves in said dials when the latter are 115 positioned with the positive zeros thereon in the reading line.
